YARN TENSIONING DEVICE

Edward J. Heizer, Mountain Lakes, and Edward A. Wentz, Montclair, N. J., assignors to Specialties Development Corporation, Belleville, N. J., a corporation of New Jersey

Application October 4, 1952, Serial No. 313,164

2 Claims. (Cl. 242—149)

The present invention relates to yarn tension compensating devices, and, more particularly, to a device for uniformly tensioning yarn, such as tire cord, prior to impregnating, stretching and drying the yarn.

Heretofore, it has been proposed to tension yarn in preparation for processing the same in the aforementioned manner by a device generally comprising a roll having a peripheral yarn receiving groove, a pivotally mounted arm having a yarn guide at one end, a snubbing roller rotatably mounted on the arm positioned to extend into the groove with the yarn between the roller and the bottom of the groove, and resilient means for urging the arm in a direction to cause the roller to extend into the groove and apply pressure on yarn in the groove.

While this device tensioned the yarn in the desired manner, it was found that the bearing for rotatably mounting the snubbing roller was subjected to considerable wear whereby the roller would tend to drag and cause yarn to be pinched between the sides of the roller and the sides of the groove. Such pinching impaired the yarn, and caused frequent breakage which necessitated stoppage of the yarn processing apparatus. Since fifty ends of yarn usually are processed simultaneously, each end being tensioned by an individual snubbing roller cooperating with a common multi-grooved roll, the breakage of one end delayed the processing of all of the ends and greatly reduced the output of the apparatus.

Accordingly, an object of the present invention is to provide a device for putting yarn under a relatively high uniform tension which is not subject to the foregoing difficulties and objections.

Another object is to provide such a device which does not impair the yarn or cause frequent breakage thereof.

Another object is to provide such a device which is readily threaded.

A further object is to provide such a device which is simple in construction and is economical to manufacture and install.

A still further object is to provide such a device which is practical and reliable in operation and can withstand continuous usage for a long period of time.

Other and further objects of the invention will be obvious upon an understanding of the illustrative embodiment about to be described, or will be indicated in the appended claims, and various advantages not referred to herein will occur to one skilled in the art upon employment of the invention in practice.

In accordance with the invention, the foregoing objects are accomplished by providing a yarn tensioning device which generally comprises a roll having a cylindrical surface, an arm having a yarn guide at one end, means for pivotally mounting the arm, a shoe mounted on the arm having an arcuate surface conforming substantially to the surface of the roll, and resilient means for urging the arm in a direction to cause the shoe to engage the roll, whereby yarn passing between the shoe and the roll surfaces is adapted to be tensioned.

2

A preferred embodiment of the invention has been chosen for purposes of illustration and description, and is shown in the accompanying drawings, forming a part of the specification, wherein:

Fig. 1 is a fragmentary perspective view of a yarn tensioning device in accordance with the invention, the lower portion thereof not being shown.

Fig. 2 is a plan view of the device, with a portion of the top broken away.

Fig. 3 is an enlarged schematic view of one set of the yarn tensioning elements, illustrating the operation of the device.

Fig. 4 is a sectional view taken along the line 4—4 on Fig. 3, illustrating a shoe positioned against the roll.

Fig. 5 is a sectional view taken along the line 5—5 on Fig. 3, illustrating a detail of the yarn tensioning elements.

Referring to the drawings in detail, there is shown a device for tensioning a plurality of ends of yarn, for example, fifty ends, it being understood that the features of the device shown may be embodied in other devices designed to tension a single end or any other desired number of ends of yarn.

The device comprises a base or supporting structure having a generally rectangular top or platform 10 and upright legs 11, 12, 13 and 14 at the corners thereof (Fig. 1). The legs 11 and 12 are channel-shaped and each has a slot 15 in the web at the upper end thereof. A pin, shaft or axle 16 extends horizontally through the side flanges of each of these legs adjacent the slot for pivotally mounting a frame about to be described.

The frame comprises a pair of parallel side members 20, each of which is supported in one of the legs 11 or 12 by one of the pins 16 for pivotal or rocking movement in a vertical plane; a horizontal shaft 21 mounted in bearings 22 secured to the side members, respectively, adjacent their upper ends, a horizontal shaft 24 mounted in bearings 25 secured to the side members, respectively, adjacent their lower ends, and a horizontal bar or rod 26 having its ends secured to the side members, respectively, adjacent their upper ends and having yarn guide fingers 27 thereon.

The upper shaft 21 has a roll 30 mounted thereon for rotation therewith and has a pulley or sprocket 31 at one end thereof adapted to be driven by suitable drive mechanism (not shown) to rotate the shaft and the roll. The yarn is drawn over the roll 30, as indicated by the arrows applied thereto in Fig. 3, by mechanism not shown herein, and the roll 30 is caused to rotate in the direction in which the yarn is drawn, but at a somewhat slower surface speed than the lineal speed of the yarn, whereby sliding friction between the roll and the yarn tensions the latter.

The roll 30 has a substantially smooth cylindrical surface about which the ends of yarns pass, and consequently can be produced at a lower cost than a roll having peripheral grooves therein.

Yarn tensioning means cooperating with the roll 30 include a plurality of arm units or assemblies 34 corresponding in number to the number of ends passed about the roll. These arms are pivotally mounted and arranged side by side on a rod 35 which is supported by a series of brackets 36 secured to the top 10, the rod 35 being parallel to the roll supporting shaft 21.

As illustrated more particularly in Figs. 3 to 5, the arm units 34 each comprise a pair of arm members 37 and 38 pivotally mounted on a bushing 40 having a side flange 41 and a retaining ring 43 secured thereto for connecting each set of arm members as a unit and the bushing having the rod 35 extending therethrough.

The arm members 37 extend upwardly a substantial distance above the roll 30 to provide a desired mechanical

advantage, and the upper portions thereof are curved to extend over the roll and each have a yarn guide 42 at the free end thereof. A stop, such as pin 44, is provided on each of the arm members 37 between the upper end and the pivot rod 35.

The arm members 38 are shorter than the arm members 37, and each has its upper end 45 formed and arranged to engage the pin 44 of the longer arm member 37 associated therewith under the influence of resilient means such as a spring 46 connected to the lower ends of each set of arm members 37 and 38. Each of the arm members 38 has a shoe 47 pivotally mounted thereon intermediate the upper end thereon and the pivot rod 35 by means of a stud 48. The shoe 47 is in vertical alignment with the guide 42 of its arm unit.

The arms units 34 are each urged in a direction to cause the shoes 47 to engage and apply pressure on the ends of yarn passing over the surface 32 by a spring 49 having one end connected to the lower end of the arm member 37 and having its other end connected to the side of the top 10 opposite the roll 30. Preferably, the springs 49 each are arranged to adjust the tension thereof by a threaded sleeve 50 having the spring attached thereto and a bolt or screw 51 anchored on the supporting structure and extending into the sleeve, whereby threading of the sleeve 50 on the bolt 51 results in adjustment of the effective tension of the spring. In this manner, the tension springs are adjustable individually to cause each arm unit 34 through its shoe 47 to apply the same tensioning force on the ends of yarn.

In order to limit the pressure which can be applied by the shoes 47 on the yarn, the springs 46 are somewhat weaker than the springs 49 and are thereby adapted to yield and permit pivotal movement of the arm members 37 and 38 with respect to each other when the tension applying force of the springs 49 becomes excessive. In this manner, the shoes 47 are prevented from applying an excessive snubbing force which might impair the yarn.

The shoes 47 are constructed of high carbon steel, such as tool steel, which is adapted to be hardened throughout; and are in the form of platelike elements having an arcuate surface 52 of considerable width conforming substantially to the contour of the surface 32 of the roll, that is, the surfaces 32 and 52 have about the same radius. The shoe surfaces 52 are polished smooth, and have rounded end and side edges which prevent the yarn from being impaired when drawn between the roll surface and the shoe surfaces, as described hereinafter. For the purpose about to be made apparent, the shoes have a toe section 53 (Fig. 3) adjacent the lower end of the arcuate surface, and a passageway 54, through which the yarn is guided, extends upwardly through this toe section with its upper end terminating at the surfaces 52 adjacent its lower end. Pivotal movement of the shoes 47 is limited by providing the same with a thickened section 57 (Fig. 4) adjacent the surface 52 adapted to engage the edge of the arm member 38 facing the roll 30.

As shown in Fig. 3, the yarn passes under the roll 30, upwardly through the shoe passageway 54 and between the roll surface and shoe surface 52, and then over a yarn guide 42, whereby a desired output tension is put into the yarn. Should the output tension exceed its desired predetermined value, the upper portion of the arm member 37 is moved slightly clockwise, as viewed, about its pivot rod 35 in opposition to the spring 49, and carries with it the arm member 38 by reason of the stop pin 44 to move the shoe 47 slightly away from the roll 30 to lessen the snubbing effect thereof on the yarn, whereby the output tension is adjusted to its desired predetermined value.

Excessive movement of the arm units 34 in such a clockwise direction is prevented by a rod or bar 55 supported between the brackets 36, parallel to and below the rod 35, which is adapted to be engaged by the lower ends of the arm members 38.

In the event the input tension of an end of yarn should

suddenly become of a high value, for example, due to snagging at its source of supply, the arm member 37 for such strand is moved in a clockwise direction until its arm member 38 engages the bar 55, whereby the shoe 47 of the latter arm member is moved away from the roll 30 a considerable distance. Should the end be subjected to a tension causing it to break, the spring 49 will rock the arm in a counterclockwise direction and the shoe 47 will re-engage the roll surface with at least a section of the yarn end therebetween. Damage to the yarn is prevented when this occurs, in spite of the rapid return of the arm member 38 under the influence of its spring 49, by reason of the pivoted mounting of the arm members 37 and 38 and the spring 46 connecting the lower ends of these arm members. For example, when the shoe engages the yarn, movement of the arm member 38 stops and the inertia force of the arm member 37 tending to rock it in a counterclockwise direction (as viewed in Fig. 3) is opposed by the force of the spring 46 which thus functions as shock absorbing means.

As previously mentioned, the springs 46 have another advantageous function in that they prevent excessive pressure on the yarn by the shoes 47 should the springs 49 be overloaded. Should such a condition exist, the springs 46 will yield and the arm members 37 will be rocked in a counterclockwise direction with respect to the arm members 38 (as viewed) by the springs 49, whereby the pressure applied to the yarn by the shoes will be limited by the weaker springs 46.

In order to facilitate threading the yarn through the passageways 54 of the shoes, the frame supporting the roll shaft 21 is arranged to be rocked about its pivot pins 16 in a direction to move the roll 30 away from the shoes 47 of the arm units. In threading the machine, the ends of yarn need only be passed through the passageway 35 and need not be placed against the shoe surfaces 52 because, upon operation of the machine, the ends are tensioned and are pulled between the roll and the shoe surfaces. The rounded edges of the shoe surfaces prevent the yarn from being impaired when so drawn into position.

The arm units are prevented from following the roll 30 by a rod or bar 56 supported between the brackets 36, parallel to the rod 55 but at the opposite side of the lower ends of the arm units, which is adapted to be engaged by the lower ends of the arm members 37 (Fig. 3).

Suitable mechanism for so rocking the frame may comprise a pair of pneumatic or hydraulic cylinders 59 (only one of which is shown) each having one end pivotally connected at 60 adjacent the legs 13 and 14, respectively, a piston in each cylinder (not shown), and a piston rod 61 extending outwardly of each piston and having its free end journalled to the shaft 24 of the frame at 62. The pistons in the cylinders are adapted to be moved simultaneously (in either direction) to move the roll outwardly or to return the same, under the control of a suitable valve 64, operated by a handle 65. The valve is operatively connected to a pressure medium supply line 66 and to the cylinders in any conventional manner.

From the foregoing description, it will be seen that the present invention provides a simple and practical yarn tensioning device adapted for putting a substantial tension of a uniform value in a single end or a plurality of ends of yarn. The yarn tensioning elements are readily adjusted, are constructed and arranged to prevent impairment of the yarn, and are readily threaded. The device is rugged in construction and can withstand such rough usage to which it may normally be subjected without replacement or repair of parts.

As various changes may be made in the form, construction and arrangement of the parts herein, without departing from the spirit and scope of the invention and without sacrificing any of its advantages, it is to be under-

stood that all matter herein is to be interpreted as illustrative and not in any limiting sense.

We claim:

1. In a yarn tensioning device, a roll having a cylindrical surface adapted to rotate about its longitudinal axis, an arm having a yarn guide at one end, means for pivotally mounting said arm, said axis of said roll being in a plane spaced from and parallel to the axis of said mounting means, a shoe pivotally mounted on said arm having an arcuate recess provided with a surface conforming substantially to the contour of the surface of said roll and in registry therewith and having a toe section formed with a yarn guiding aperture extending through said toe section from one end of said shoe and

10

terminating at said arcuate surface, and yieldable means for urging said arm in a direction to cause said shoe to engage said roll, whereby yarn passing between said shoe and said roll surfaces is tensioned.

2. A device according to claim 1, wherein said arcuate surface is smooth and has rounded side and end edges.
